UNITED STATES PATENT OFFICE.

FREDERICK A. BREDEL AND JOHN BERGMANN, OF ST. LOUIS, MISSOURI; SAID BERGMANN ASSIGNOR TO SAID BREDEL.

COKE-OVEN.

1,255,579.

Specification of Letters Patent. Patented Feb. 5, 1918.

Application filed August 22, 1916. Serial No. 116,841.

To all whom it may concern:

Be it known that we, FREDERICK A. BREDEL, a citizen of the United States, and JOHN BERGMANN, a citizen of Germany, both residing in the city of St. Louis and State of Missouri, have invented a certain new and useful Improvement in Coke-Ovens, of which the following is a full, clear, and exact description, such as will enable others skilled in the art to which it appertains to make and use the same.

This invention relates to coke ovens of the type in which the chambers that receive the coal which is to be converted into coke are arranged in an inclined position.

One objectionable feature of coke ovens of the type referred to that are now in general use is that the coal chambers of same are of such form that when the coal 20 expands or swells, during the operation of driving off the gases, the top walls of the coal chambers are subjected to abnormal strains or pressures, due to the increase in bulk of the coal contained in the chambers.

The main object of our invention is to provide an inclined coke oven which is so designed that the top walls of the coal chambers will not be subjected to undue pressure or strains from the coal in same, during the 30 operation of converting the coal into coke. To this end we have devised a coke oven equipped with one or more inclined coal chambers, each of which is provided with a top wall which is so designed that the coal 35 in the chamber can expand or swell during the coking operation, without causing the coal to exert an abnormal or undue pressure on the walls of the coal chamber.

And another object of our invention is 40 to provide an inclined coke oven having a coal chamber that is provided with means for permitting the gases to escape therefrom at one or more points intermediate the ends of the chamber.

Figure 1 of the drawings is a vertical sectional view of a coke oven constructed in accordance with our invention, taken on the line A—A of Fig. 2; and

Fig. 2 is a vertical transverse sectional 50 view of said coke oven, taken approximately

on the line B—B of Fig. 1, the upper right hand portion of said view being taken on the line C—C of Fig. 1.

Referring to the drawings, which illustrate the preferred form of our invention, 55 9 designates the coal chambers of the oven which are arranged in an inclined position, as shown in Fig. 1, each of said chambers being provided at its upper end with a feed opening 2 through which coal is introduced 60 into the chamber and provided at its lower end with a door 3 that normally closes a discharge opening through which the coke is removed from the chamber. The top wall of each of the coal chambers 9, instead of 65 being arranged parallel with the bottom wall of the chamber, as has heretofore been the general practice in inclined coke ovens, is constructed in such a manner that the coal in said chamber will not contact with 70 the top wall of the chamber throughout the entire area of said top wall when the chamber 9 is filled with coal, preparatory to the operation of heating the coal to convert it into coke. The top wall of the coal chamber 75 can be formed in various ways without departing from the spirit of our invention, but in practice we prefer to provide the top wall of the chamber 9 with one or more offsets 6, so as to form a relief space or 80 spaces above the top surface of the pile of coal in the chamber. In the form of our invention herein shown the portion 8 of the top wall of the chamber 9 adjacent the lower end of the chamber is spaced farther 85 away from the bottom of the chamber than the portion 7 of said top wall adjacent the upper end of the chamber, thus producing the offset 6 in the top wall that forms a relief space above the top surface of the pile 90 of coal in the chamber. When the bulk of the coal in the chamber 9 increases, due to expansion or swelling of the coal, during the coking operation, the relief space or 95 spaces above the top surface of the pile of coal permits the coal to shift sufficiently to prevent the top wall of the chamber 9 from being subjected to undue strains. In other words, when the coal expands, or 100 swells, some of the coal will be forced up-

wardly into the relief space in the top wall of the coal chamber, and thus prevent the mass of coal in the chamber 9 from exerting sufficient pressure on the walls of the chamber to disrupt or weaken same.

In order that the gases may escape freely from the chamber 9 during the coking operation, we have provided the coal chambers, at points intermediate the ends of same, 10 with auxiliary gas outlet ports 17. In the form of our invention herein shown, in which the top wall of each coal chamber is provided with only a single offset 6, an auxiliary gas outlet port 17 is formed in the 15 offset portion of the top wall, so as to permit the gases generated in the lower portion of the chamber 9 to escape therefrom freely. The gases that are generated in the upper portion of the chamber 9 escape therefrom through a conduit 1. If desired, the auxiliary gas outlet port 17 intermediate the ends of the chamber 9 can be connected with the main gas outlet port at the upper end of said chamber by means of a gas passage-way 5, as shown in Fig. 1.

The coal chambers 9 of the oven are heated by gas generated in a gas producer located at the rear of the oven, as shown in Fig. 1, and provided with a fuel chamber 14 30 to which fuel is supplied through a feed opening 13 at the upper end of said fuel chamber. Each of the coal chambers 9 of the coke oven is provided at its rear end with a coke discharge passage way 15 that is 35 inclined downwardly, so that coke can escape through same from the chamber 9 when the door 10 at the lower end of said passageway is opened, the door 10 being normally closed. When it is desired to supply fuel to the producer, the door 10 of one 40 of the coal chambers is opened, so as to permit coke to escape by gravity from the chamber and enter a device that conveys or conducts the coke to the fuel feed opening 45 13 of the gas producer. Any suitable means may be used for conveying or conducting the coke from the coke discharge passageway 15 to the fuel feed opening 13 of the gas producer, such, for example, as a car 11 that 50 travels on rails arranged at the rear side of the oven above the gas producer and provided with a hopper 12 into which the coke is discharged from the passageway 15 when the door 10 that controls said passageway 55 is opened. A single car 11 may be used with a battery of coke ovens, and after the car has been positioned properly with respect to the coal chamber 9, from which the coke is to be taken, the hopper 12 of the car is 60 filled with coke by opening the door 10 of the chamber, the coke passing from the hopper of the car into the fuel opening 13 of the gas producer. This feature of the oven forms no part of our present invention, how-

ever, as we have claimed said feature in our 65 co-pending application Serial No. 116,242, filed August 22, 1916.

While we have herein illustrated our invention embodied in an inclined coke oven of conventional design, so far as most of the 70 elements of the oven are concerned, we wish it to be understood that the particular details of construction of the oven, other than the shape or form of the top wall of the coal chamber, are immaterial, and that while 75 we have herein illustrated said top wall provided with only a single offset that forms a relief space above the coal, said top wall could be provided with a plurality of such offsets, or could be formed in various ways, 80 without departing from the spirit of our invention. Furthermore, instead of providing the coal chamber with only a single auxiliary gas outlet port, said chamber could be provided with a plurality of such ports arranged intermediate the upper and lower 85 ends of the chamber, so as to permit the gases to escape freely from different zones or sections of the coal chamber.

Having thus described our invention, 90 what we claim, and desire to secure by Letters Patent, is:

1. A coke oven having an inclined coal chamber that is adapted to be filled with coal, the bottom wall of said chamber being 95 straight or continuous and top wall of said chamber being provided on its inner side with an offset for the purpose described.

2. A coke oven having an inclined coal chamber whose bottom wall is straight or 100 continuous and whose top wall is rigid and composed of sections, the inner sides of which are located different distances from the straight bottom of the chamber.

3. A coke oven having an inclined coal 105 chamber whose bottom wall is straight and whose inner top wall is composed of a plurality of rigid malalining sections so that when said chamber is filled with coal one of said sections will be spaced away from the 110 upper surface of the pile of coal in the chamber, thereby providing a relief space that eliminates the liability of said top wall being subjected to undue strains when the bulk of the coal is increased during the coking 115 operation.

4. A coke oven having an inclined coal chamber whose bottom wall is straight or continuous and whose top wall is provided on its inner side, intermediate its ends, with 120 an offset that connects two portions of said top wall whose inner surfaces are located different distances from the bottom of the chamber.

5. A coke oven having an inclined coal 125 chamber whose bottom wall is straight and whose top wall is rigid and provided on its inner side with an offset, located interme-

diate the upper and lower ends of the chamber, and a gas outlet formed in the offset portion of said top wall.

6. A coke oven having a coal chamber 5 whose bottom wall lies in a continuous inclined plane, and whose top wall is composed of a plurality of sections lying in in-

clined planes differing from the plane of the bottom wall, and a substantially horizontally-disposed section joining said upper 10 inclined planes so as to form an offset for the purpose described.

FREDERICK A. BREDEL.
JOHN BERGMANN.
